R. B. ELLEDGE,
DESK.
APPLICATION FILED NOV. 22, 1920.

1,374,070.

Patented Apr. 5, 1921.

UNITED STATES PATENT OFFICE.

ROBERT B. ELLEDGE, OF TAMPA, FLORIDA.

DESK.

1,374,070.

Specification of Letters Patent.

Patented Apr. 5, 1921.

Application filed November 22, 1920. Serial No. 425,820.

To all whom it may concern:

Be it known that I, ROBERT B. ELLEDGE, a citizen of the United States, residing at Tampa, in the county of Hillsborough and 5 State of Florida, have invented new and useful Improvements in Desks, of which the following is a specification.

My present invention has reference to a desk attachment for beam scales or the like.

10 My object is to produce a desk attachment of this character which may be easily attached to the beam of a scale or other support and firmly secured thereon.

15 A further object is the construction of a desk which may be in the nature of a plate that has its edges reinforced, certain of the reinforcements providing means whereby the desk may be removably attached to a support, another of said reinforcing means 20 properly sustaining a clip on the desk plate whereby note sheets may be sustained thereon, while the desk plate is provided with additional means for also retaining the said sheets thereon.

25 The foregoing, and other objects which will appear as the nature of the invention is better understood, may be accomplished by a construction, combination and operative arrangement of parts, such as is disclosed 30 by the drawings which accompany and which form part of this application.

In the drawings:—

Figure 1 is a perspective view illustrating the application of the improvement.

35 Fig. 2 is a sectional view taken in a line with one of the reinforcements for one of the edges of the desk plate, the said reinforcement also providing means for sustaining the desk plate on the support, said section 40 being approximately on the line 2—2 of Fig. 1.

Fig. 3 is a perspective view of the spring sheet retainer.

45 Fig. 4 is a sectional view through the clip and reinforcing rod at the lower portion of the body plate.

While I have illustrated my improved detachable and reversible desk applied to the bottom of an ordinary platform scales, and 50 for which purpose it is primarily devised, it is to be understood that the invention is not to be limited to such application, as the same may be found convenient in connection with devices other than scales. In each 55 event, however, the desk is attached to a suitable support.

The upper beam of a scale is indicated, in the drawing, by the numeral 1. This beam has its sides provided with oppositely disposed spaced pairs of apertures 2.

My improved removable and reversible desk may be wholly constructed of metal. The desk includes a body plate 3 that has its ends and edges rolled to provide beads. Passing through the beads are reinforcing 60 rods. The rods that pass through the end beads are indicated by the numeral 4, the same extending below the body plate and having angle ends which provide hooks 5.

The hooks are designed to be received in the 70 apertures 2 on one of the sides of the beam 1. The upper portions of the rods 4 are rounded upon themselves and extend angularly over the rear of the body plate 3. These angle extensions are indicated by the 75 numeral 6. The portions 6 are designed to exert a tension toward the portions 4. The portions 6, adjacent to the outer ends thereof are bent at a further outward angle, as indicated by the numeral 7, and from thence are 80 bent inwardly, as at 8, to provide hooks that are arranged opposite the hooks 5. These last mentioned hooks 8 are designed to be arranged in the apertures on the side of the beam opposite those receiving the hooks 5, 85 and by this arrangement, it will be noted that the body plate 3 is sustained at an upward angle on the beam, and is effectively clamped thereto. It will, of course, be apparent that by spreading the limb 6, of 90 the spring reinforcing rod 4, outward with respect to the body plate, the hooks 8 and 5 may be readily removed from the openings in the side faces of the beam.

In the lower bead provided by the rolled 95 portion of the plate 3, there is a reinforcing rod 9, and in the upper bead there is a reinforcing rod 10.

The lower bead has its end contacting with the outer face of the body plate, but is 100 from thence extended at an outward angle from the said body plate, as indicated by the numeral 11. This portion 11 provides a spring clip, being part of the body plate and necessarily embodying inherent resiliency. 105 The sheets of paper engaged by the spring clip 11 will be effectively held against the body plate. However, to support the upper portions of the letter sheets, I pivotally secure, as at 14, adjacent one of the upper corners of the said body plate, a spring rod 12. 110 This rod has one of its ends bent upon itself

to provide an eye 13 through which the pivot member 14 passes. The rod is designed to exert a tension toward the body plate.

5 In addition to providing means for supporting the lower edges of the paper sheets on the desk, the clip 4 may serve as a pocket or receptacle for a writing implement, and while I have, in the drawings, shown the device supported vertically on the beam 1, it will be apparent that the same may be supported horizontally, if desired. The device, as illustrated, is arranged at a slight inclination with respect to the beam 1, and 10 does not in any way interfere with the reading of the scale.

15 It is believed that the foregoing description, when taken in connection with the drawings, will fully set forth the simplicity 20 and advantages of the improvement without further detailed description.

Having thus described the invention, what I claim, is:—

25 1. In combination with a support having apertures on both sides thereof, of a removable desk therefor, comprising a plate having rolled edges and ends, reinforcing rods therein, the rods in the ends extending above and below the plate and having their lower 30 ends bent angularly to provide hooks that enter the apertures on one side of the sup-

port, the upper ends of the said rods being rounded and extended over the rear end of the plate and having their lower portions bent outwardly and from thence bent inwardly to provide hooks which enter the apertures on the opposite side of the support. 35

2. In combination with a support having oppositely disposed apertures on the opposite sides thereof; of a removable desk, comprising a plate having rolled edges and ends, reinforcing rods in the said rolled portions, the end reinforcing rods extending through the corners of the plate and having their lower portions inturned to provide hooks which enter the apertures on one of the sides of the support, the upper ends of the said rods being rounded upon themselves and extended angularly from the rear of the plate 45 and having their ends bent inwardly to provide hooks which are disposed opposite the first mentioned hooks and which enter the apertures on the second side of the support, said plate at its lower rolled end having an 50 angular extension which provides a spring clip, and a spring rod disposed over the face of the plate and having one of its ends pivotedly secured adjacent one of the corners of the plate. 55

60 In testimony whereof I affix my signature.

ROBERT B. ELLEDGE.
